Patented Jan. 23, 1917.

UNITED STATES PATENT OFFICE.

ENOCH RECTOR, OF NEW YORK, N. Y., ASSIGNEE TO RECTOR ENGINE CORPORATION, OF NEW YORK, N. Y., A CORPORATION OF NEW YORK.

HYDROCARBON-BURNER.

1,213,412.

Specification of Letters Patent. Patented Jan. 23, 1917.

Application filed February 26, 1912, Serial No. 679,864. Renewed June 15, 1916. Serial No. 103,865.

To all whom it may concern:

Be it known that I, ENOCH RECTOR, a citizen of the United States, residing in the borough of Manhattan, in the city of New York, in the State of New York, have invented certain new and useful Improvements in Hydrocarbon-Burners, of which the following is a specification.

This invention relates to hydrocarbon burners using the self-generated gases of petroleum, gasoline and similar volatile hydrocarbons.

The primary object of the invention is to provide a burner capable of generating and consuming a large quantity of a gas or vapor which shall be under instant control whereby the size of the flame can be immediately adjusted to momentary requirement.

20 A further object of the invention is to provide means whereby the burner may be throttled so as to consume a very small quantity of gas and yet produce a blue flame of high heat producing capacity in a zone 25 remote from its outlet.

Another object of the invention is to produce an apparatus in which a reservoir or supply of gas is automatically maintained and the flow of gas shall be under 30 approximately uniform pressure.

Still another object of the invention is to provide an arrangement and combination of parts whereby the valves shall not be exposed to the ignited gases and consequently 35 be protected from injury due to excessive heat, and in which the various parts of the apparatus are accessible for cleaning and the removal of any deposits that may form, and in which the apparatus may be readily 40 assembled and taken apart.

The various other objects of the invention will be more fully set forth in the following description of one form of apparatus embodying the invention, which consists in the new and novel features of the construction and combination of parts hereinafter set forth and claimed.

In the accompanying drawings: Figure 1 is a side elevation partly in section of my 50 improved burner. Fig. 2 represents a plan view of the burner. Fig. 3 is a central sectional view at right angles to Fig. 1 of the generator chamber showing the bearings for the needle valve. Fig. 4 is a front eleva-

tion of the generator chamber, and Fig. 5 is a detail view of the needle valve.

The supply pipe 1 may be arranged to pass through the flame in the normal operation of the burner and preferably over the top of the casing 2 which contains the heating and pressure chamber or reservoir 3 which is also subjected to the heat of the flame. The supply pipe is provided with a valve 1^a and is supported by any suitable means as a clamp 4 provided on the frame 5, and has its inner end threaded to engage with the casing 2 which is preferably circular in shape. An outlet pipe 7 is provided which has its inner end arranged at or near the top of the chamber 3. Said outlet pipe 7 is also preferably secured to and supported by the frame by means of clamps 8. The outer or delivery end of the pipe 7 is preferably formed by a separate pipe section 9 arranged approximately horizontal and having a tapered outlet or orifice 10 formed therein below the center of the casing 2. One end of said section is normally closed by a plug 11 which permits sediment or any deposition of carbon to be readily removed. 80

A conical gas spreading and valve bearing member or housing 14 is arranged between the casing 2 and the pipe section 9 with its apex immediately above the orifice 10. The said member is provided with a recess 15 and with a central bearing 16 for the needle valve 17 which is adapted to engage with the orifice. Said valve is operated in any well-known manner as by a shaft 18 which extends into the recess 15 through a passage 19 and is operatively connected to the needle valve in any well-known manner, as by the link 20. The free end of the valve is preferably provided with one or more corrugations or grooves 21 which permit a small quantity of gas to escape even when it is seated in the orifice. 95

Longitudinal ridges 22 project from the surface of the member 14, through the upper portion of which ridges project the supply and outlet pipes and the valve control lever, placing these members out of line of the ascending gas which is divided by the ridges thus preventing the ignition of the gas at the point of contact of the pipes and lever with the member 14. A peripheral radial flange 23 is provided on the member 14 which extends outwardly beyond the 100 105

- flanges and interrupts the ascending currents of gas. An intermediate gas interrupting device such as the baffle pins 24 may be provided which will form a baffle in case only a small quantity of gas is being used. The member 14 is supported preferably upon the supply pipe 1 and the outlet pipe 4 in any suitable manner as by means of the set screw 25.
- 10 A small cup 26 is secured preferably to the bottom of the section 9 adapted to hold sufficient liquid to heat the supply pipe enough to induce the generation of vapor when it is desired to commence the use of the burner. By opening the valves the liquid will flow out through the orifice, thus not only filling the cup 26 but covering the pipe itself with the liquid as it overflows.
- In full operation the liquid is supplied to the supply pipe 1 and is vaporized as it passes through the bent portion of the pipe which is in the flame. The vapor passes into the bottom of the pressure chamber where it is superheated and thence passes from the top of the chamber into the outlet pipe whence it escapes through the orifice 10. The gas is caused to spread as it leaves the orifice by the needle valve that is positioned immediately above the orifice in the path of the gas, which ascends until the baffle flange or plate 23 is encountered which causes the gas to mix with the air and form a suitable mixture for ignition. The baffle plate not only serves to mix the air and the gas but also tends to prevent the gas from passing beyond the plane of the baffle plate without igniting. In case it is desired to reduce the consumption of gas, and, consequently, the size of the flame, the needle valve can be operated to close or partly close the orifice, but even when the needle valve is entirely closed a relatively small quantity of gas will escape through the corrugations formed thereon, which will 45 keep the flame alive at the line of the intermediate baffle pins. The operating mechanism for the valve is arranged within the conical member so that it is completely protected from the heat of the flame, and although a suitable operating handle has been indicated on the drawing for operating the valve it is obvious that the control may be placed at any desired position through suitable levers or linkage. It is obvious also that various other changes within the skill of the mechanic may be made in the particular mechanism shown and described without departing from the spirit of the invention provided the means set forth in the 50 following claims be employed.
- I claim as my invention:
1. In a hydrocarbon burner, the combination with a gas reservoir and an outlet pipe having an orifice provided therein, of a conical member arranged adjacent to the orifice, a valve carried by said member and adapted to close said outlet, and means secured to said member for spreading the gases escaping through said orifice.
  2. In a hydrocarbon burner, the combination of a supply pipe and a gas reservoir adapted to be disposed in the flame from the burner, an outlet pipe from said reservoir, with the end thereof in the reservoir positioned above the end of the supply pipe in the reservoir whereby the gas is compelled to traverse the reservoir, said outlet pipe having an orifice below the reservoir, and a valve between the reservoir and the orifice, arranged in the path of the gases escaping from the orifice.
  3. In a hydrocarbon burner, the combination of a supply pipe, a gas reservoir, an outlet pipe having an orifice below the reservoir, and valve supporting means secured adjacent to the bottom of the reservoir and having a recess provided therein and an axial bearing communicating with said recess, a valve in said bearing, and means in the recess for operating the valve.
  4. In a hydrocarbon burner, the combination of an outlet pipe provided with a tapered orifice forming a valve seat, a valve for incompletely closing said orifice, and a support for said valve provided with a spreading means for causing the vapor to mix with the surrounding air.
  5. In a hydrocarbon burner, the combination of an outlet pipe for the vapor provided with a tapered orifice forming a valve seat, a valve supported above said orifice in the path of the vapor escaping therefrom, and conical supporting means for said valve provided with longitudinal ribs and with a radial baffle plate.
  6. In a hydrocarbon burner, the combination of an outlet pipe for the vapor provided with an orifice forming a valve seat, a valve for said orifice having a corrugation formed in its engaging face and supported above the orifice, and a gas spreading member forming a support for said valve and forming a housing to protect the valve stem from the heat of combustion.
  7. In a hydrocarbon burner, the combination of a reservoir, a supply pipe communicating with the bottom of the reservoir, an outlet pipe communicating with the top of the reservoir and having an orifice below the reservoir, a valve housing between the reservoir and orifice, said reservoir and housing being supported by the supply pipe and the outlet pipe, a valve mounted in said housing adapted to seat in said orifice, and means on the housing for spreading the vapor escaping through said orifice.
  8. In a hydrocarbon burner, the combination of a reservoir, an inlet pipe communicating with the bottom of the reservoir, an outlet pipe communicating with the top of the reservoir.

the reservoir and having an orifice below the reservoir, a conical valve housing between the reservoir and the orifice and having its apex above the orifice, said housing being provided with a recess and an axial valve bearing in communication with said recess, a valve mounted in said bearing and adapted to seat in the orifice, operating mechanism for said valve mounted in said

recess, and a plurality of gas interrupting devices radially arranged on said housing above the orifice.

This specification signed and witnessed this 14th day of Feb., A. D. 1912.

ENOCH RECTOR.
